Alonzo B. Bailey of Middle Haddam Conn. **DES. 2387**
Letters Patent No. 2387. Dated Aug. 14. 1866.
Design for Coffin Handles

The schedule referred to in this Letters Patent and making part of the same.

To all whom it may concern:

Be it known that A. Alonzo B. Bailey of Middle Haddam in the County of Middlesex and State of Connecticut, have invented a new and improved Design for Coffin Handles; and I do hereby declare that the following is a full, clear, and exact description thereof, which will enable others skilled in the art to make and use the same, preference being had to the accompanying drawing forming part of this specification.

The present invention relates to a new and improved Design for a handle to be used upon Coffins, bier-cases, or caskets, and other similar receptacles employed for the burying of the dead which Design is illustrated in the accompanying plate of drawings, the figure being a front view of the same.

It, in the drawings represents the handle bar which is made of a semicircular shape terminating at each end in similar arms B, B, by which it is hung and turned in the socket or cap plates C, C. The handle bar at each end beyond its arms B, is similarly ornamented with a drop D, consisting of an acorn E, and oak leaves F.

The socket or cap plates C, are ornamented around the projecting portions G, of the same, in which the handle turns or swings with a series of oak leaves F, and the said projecting portions G, are of an acorn shape and design.

I claim as new and desire to secure by Letters Patent, the Design for a handle herein described and shown in the drawings.
